UNITED STATES PATENT OFFICE.

GEORGE K. McNEILL, OF DETROIT, MICHIGAN, ASSIGNOR TO MORGAN & WRIGHT, OF DETROIT, MICHIGAN, A CORPORATION OF MICHIGAN.

APPARATUS FOR REMOVING VULCANIZING BAGS.

Application filed February 23, 1924. Serial No. 694,519.

To all whom it may concern:

Be it known that I, GEORGE K. McNEILL, a citizen of the United States, and a resident of Detroit, county of Wayne, and State of Michigan, have invented a certain new and useful Apparatus for Removing Vulcanizing Bags, of which the following is a full, clear, and exact description.

This invention relates to a machine for removing vulcanizing bags from casings. It aims to provide a simple, inexpensive, labor-saving and readily manipulated appliance for economically withdrawing so-called "water bags" from casings.

The invention, briefly stated, consists in a supporting holder for the casings, including a hook element into which a nested casing and bag may be readily introduced so that a second hook may be engaged with the bag in opposition to the first hook, which is engaged with one side of the casing, and may be pulled upon to strip the bag from within the casing.

An embodiment of the invention is illustrated in the accompanying drawings, in which:

Figure 1 is a perspective view of the apparatus;

Figure 2 shows the first step in mounting a nested casing and bag;

And Figure 3 illustrates the parts when the bag has been partly drawn out of the casing.

The apparatus comprises a frame, indicated generally by the numeral 1, consisting of structural steel parts bolted or riveted together in any manner convenient, not requiring detailed explanation. To a cross-bar 2 of the frame is secured a downwardly directed hook 3, preferably with provision for adjustment provided by the slot and bolt connections indicated at 4. This adjustment facilitates the apparatus for tires of different sizes. At opposite sides of the hook 3 are more or less upright arms or rests 5, carrying preferably fairly broad plates 6, affording an abutment against which the casing 7 may lie and be pulled upon without scar or injury. Lengthwise and at opposite sides of the frame 1, are guide-rods 8, which are suitably secured to the cross-bars 2. These afford guides for a cross-head or sliding member 9 to which at 10 is pivoted a hook 11 normally held in the raised position shown in Figure 1 by a

spring 12. This construction permits the hook 11 to be moved manually down past the hook 3 and between the casing 7 and the vulcanizing bags 13 nested therewithin.

While the cross-head 9, carrying the hook 11, may be actuated in any suitable manner, it is preferred to employ a pneumatic (or hydraulic) cylinder 14 whose piston rod 15 is connected directly with the cross-head, the axis of the cylinder 14 being parallel with the guide-rods 8. The cylinder 14 may be secured rigidly in any suitable manner to the frame 1. Through a foot treadle 16, a rod 17, bell-crank 18, rod 19 and crank shaft 20, any convenient type of valve mechanism 70 may be actuated to control the admission and exhaust of fluid under pressure to and from the opposite ends of the cylinder 14. In the preferred construction, depression of the treadle 16 retracts the hook 11 away 75 from the hook 3 and release of the foot treadle 16 returns the hook 11 to the starting position in proximity or adjacent the hook 3.

In operation the nested bag and casing 80 are placed in position with the hook 3 engaging one of the bead portions of a casing. This may be done conveniently by canting the tire forward somewhat, as illustrated in Figure 2 of the drawings. Then, the operator manually moves the hook 11 from the raised position shown in Figure 1 down past the hook 3 and between the bag 13 and the casing 7. By resting his weight upon the hook 11, the operator can insert it sufficiently 90 to get a good grip on the bag 13. While maintaining the pressure of his weight upon the hook 11, the operator then depresses the foot treadle 16 so as to supply fluid under pressure to the proper end of the cylinder 14. 95 and thereby draw the hook 11 away from the hook 3. This results in forcibly pulling the bag and stripping it out of the casing. The bag 13 falls upon the inclined platform 21 and is deflected to one side out of the way. 100

The invention is not limited to the precise construction and arrangement described above and illustrated in the drawings, and reference should therefore be made to the appended claims for a full understanding 105 of its scope.

Having thus described my invention, what I claim and desire to protect by Letters Patent is:

1. An apparatus for removing vulcanizing 110

5 bags from casings comprising, in combination, means engageable with a bead portion of a casing at one side thereof, rests for the opposite side of the casing, and power operable means manually engageable with a bag within the casing for pulling the two apart.

10 2. An apparatus for removing vulcanizing bags from casings comprising, a frame, a hook fixed to the frame, arms secured to the frame on opposite sides of the hook and therewith constituting a supporting holder for an annular casing, a manually and bodily movable hook, and means for moving the latter bodily whereby a bag may be pulled 15 out of a casing.

20 3. An apparatus for removing vulcanizing bags from casings comprising, a frame, a hook fixed to the frame, arms secured to the frame at opposite sides of the hook and therewith constituting a supporting holder for an annular casing, a member slideable on the frame away from said hook, a second hook movably mounted on the member for engaging a bag in proximity to said first- 25 mentioned hook, and means for shifting said member away from the first-mentioned hook whereby a bag may be pulled out of a casing.

30 4. An apparatus for removing vulcanizing bags from casings comprising, a frame, a hook fixed to the frame, arms secured rigidly at opposite sides of the hook and therewith constituting a supporting holder for an annular casing, a second hook movable transversely of the supporting holder 35 and in a line passing in proximity to the

fixed hook, said second hook being also manually movable in a plane perpendicular to that defined by the supporting holder for the casing, and means for moving the second hook.

40 5. An apparatus for removing vulcanizing bags from casings comprising, a fixed hook, a movable hook, means for shifting the movable hook away from the fixed hook, rests at opposite sides of the fixed hook and 45 therewith constituting therewith a supporting holder for a casing, and a spring normally holding said second hook in an elevated position but permitting it to be manually moved into proximity with the first-mentioned hook 50 whereby a bag may be pulled out of a casing.

55 6. An apparatus for removing vulcanizing bags from casings comprising, a frame, a hook fixed to the frame, arms secured to the frame at opposite sides of the hook and therewith constituting a supporting holder for an annular casing, a member slideable on the frame away from said hook, a hook on the member for engaging a bag in proximity to said first-mentioned hook, means for 60 shifting said member away from the first-mentioned hook whereby a bag may be pulled out of a casing, and an inclined platform within the frame and below the slideable member for deflecting removed bags to 65 a non-obstructing position.

Signed at Detroit, county of Wayne, and State of Michigan, this 19th day of February, 1924.

GEORGE K. McNEILL.
